UNITED STATES PATENT OFFICE.

JOSEPH FARGESON, OF CHICAGO, ILLINOIS.

MOP-WRINGER.

1,110,616.

Specification of Letters Patent. Patented Sept. 15, 1914.

Application filed August 26, 1912. Serial No. 716,989.

To all whom it may concern:

Be it known that I, JOSEPH FARGESON, a citizen of the United States, residing at 3116 Cottage Grove avenue, in the city of Chicago, Cook county, Illinois, have invented new and useful Improvements in Mop-Wringers, of which the following is a specification.

This invention relates to mop wringers of the kind comprising a suitable supporting device in which is mounted rollers or other wringing devices, the whole being secured within a bucket or tub of simple form for containing the water which is used in the mopping operation. In the ordinary operation of cleaning with a mop as for example in mopping a floor the water is supplied from a mop bucket into which the mop cloth or mop rag is dipped, and it is also necessary to occasionally wring out the rag to expel the excess water from it. For this purpose the invention is designed to provide a suitable device for attachment to the inside of the mop bucket above the surface of the water therein, such device including rollers between which the mop cloth may be passed, and simple and conveniently operated means for bringing the rollers together in order to squeeze the mop rag between them.

A device embodying the principles of the present invention is illustrated in the accompanying drawings in which:

Figure 1 is a view in axial section through the mop bucket and the wringing device, such section being taken on the line 1 of Fig. 2. Fig. 2 is a top plan view of the mop bucket with the wringing device in place. Fig. 3 is a vertical section on the line 3 of Fig. 2. Fig. 4 is a view in elevation showing one of the coiled springs for separating the rollers when pressure is removed from the operating handle.

As shown in said drawings, 1 indicates a mop bucket or pail of ordinary form which may preferably be of wood and of suitable size and proportions to contain the scrubbing water which is used to wet the mop rag or cloth. Within the pail 1 and at the upper edge thereof are secured a pair of horizontal and parallel cross frame members 2 and 3, each of which is offset at its ends to coincide with the curvature of the pail and attached at such ends to the sides of the pail 1, as by means of screws 5, 5.

A horizontal roller 8, is journaled on a sta-

tionary shaft 9 and such shaft extends from one cross frame member to the other and is secured to them at its ends; and directly above the roller 8 is a second roller 12 similarly journaled on a stationary shaft 13 which is supported by upward extensions 16 from the two cross frame members 2 and 3. The said frame members also support a third, movable, roller 20 which is rotatively mounted on a shaft 22 having its ends guided in horizontal slots in the frame members, one of which slots is shown in Fig. 1 at 23. By this means it will be seen that the movable roller 20 may be caused to approach or recede from the other two rollers, and the parts are so arranged that the movable roller moves in a horizontal plane half way between the planes of the two fixed rollers, whereby it is always equi-distant from them.

At each end of the shaft 22 is fixed a gear segment 30, the shaft being preferably tapered and squared at its ends and the hubs of the gear segments being provided with corresponding openings and fixed at the ends of the shafts by nuts 32, as best shown in Fig. 3. Each of the side members 2 and 3 is outwardly widened or flanged along its lower edge and in such widened part of each side member is formed an upwardly facing fixed rack, 35 and 36 respectively, meshing with the two gear segments. It will be seen therefore that by rotating the shaft 22 the two gear segments at its ends will travel along the fixed racks and will cause the movable roller 20 to approach or recede from the two fixed rollers 8 and 12; and for the purpose of such operation one of the gear segments is provided with an integral radial extension in the form of a lever 40 by means of which the device is operated.

Bent springs 44 are provided at each end of the shaft 22, each spring having a loop 45 at one end which encircles the shaft and being similarly shaped at the other end and fixed to a stud 48 in the adjacent frame member; and the expansion of the two springs 44 acts normally to separate the movable roller 20 from the other two, while yieldingly permitting such roller to be brought toward the other two by the operation of the lever 40.

In the use of the device the wringing operation is effected by allowing the rollers to separate and placing the mop cloth between the movable and the two fixed rollers; then

applying pressure to such cloth by means of the lever 40 as above described and drawing the mop rag upward through the rollers to squeeze out the water and drain it into the pail.

5 I claim as my invention:

1. In a mop wringer, the combination with a water container, of a pair of parallel horizontal frame members within such water container, a transverse shaft with its ends fixed in such frame members, a roller journaled on such shaft, horizontal slots in such frame members, a shaft extending through such slots, horizontal flanges on such frame members formed to provide racks, gear segments on the movable shaft meshing with such racks, and a lever fixed to one end of such movable shaft for rotating it.
- 10 2. In a mop wringer, the combination with a water container, of horizontal frame

members near the top of such water container and with their ends secured to its inner wall, racks at the lower margins of such frame members, horizontal slots above such racks, a transverse shaft having its 25 ends supported by such frame members, a roller on such shaft, another shaft having its ends extended through such slots, a roller on such second shaft, springs acting to move it away from such first roller, a handle at 30 one of its ends, and gears at both ends meshing with such racks.

In witness whereof, I have hereunto subscribed my name in the presence of two witnesses this 15th day of August, 1912.

JOSEPH FARGESON.
